US0D1086910S

(12) **United States Design Patent** (10) Patent No.: **US D1,086,910 S**
(45) Date of Patent: ** Aug. 5, 2025

(54) **BLUETOOTH TRACKER**

(71) Applicant: **Shenzhen TIZE Technology Co., Ltd.**,
Shenzhen (CN)

(72) Inventor: **Jian Wen**, Shenzhen (CN)

(73) Assignee: **Shenzhen TIZE Technology Co., Ltd.**,
Shenzhen (CN)

(**) Term: **15 Years**

(21) Appl. No.: **29/947,075**

(22) Filed: **Jun. 13, 2024**

(51) LOC (15) Cl. **10-05**

(52) U.S. Cl.

USPC **D10/70**

(58) **Field of Classification Search**

USPC D10/104.1, 104.2, 106.1, 106.5, 106.9,
D10/106.91, 106.94

See application file for complete search history.

(57) **CLAIM**

The ornamental design for a Bluetooth tracker, as shown and described.

DESCRIPTION

FIG. 1 is a front perspective view of a Bluetooth tracker, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the Bluetooth tracker, which form no part of the claimed design.
